[57] CLAIM

The ornamental design for a bottle, as described and shown.

DESCRIPTION

FIG. 1 is a perspective view of a bottle embodying our new design, with the closure being depicted in phantom;
FIG. 2 is a front elevational view of the bottle of FIG. 1;
FIG. 3 is a side elevational view to the left of the view of FIG. 2;
FIG. 4 is a side elevational view opposite the view of FIG. 3;
FIG. 5 is a top plan view;
FIG. 6 is a bottom plan view;
FIG. 7 is a sectional view of the bottle from the view of FIG. 2, taken along lines 7—7;
FIG. 8 is a front elevation of an alternate embodiment of the bottle, the rear elevation is a mirror image thereto;
FIG. 9 is a side elevational view to the left of the view of FIG. 8;
FIG. 10 is a side elevational view opposite the view of FIG. 9; and,
FIG. 11 is a top plan view thereof.
The bottom of the second embodiment is the same as the bottom of the first embodiment.
The broken lines in the drawings are for illustrative purposes only and do not form part of the claimed design.
